BODY SUPPORT FOR USE IN SHAMPOOING THE HAIR OR THE LIKE

Pauline Rankin, 201 NE. 6th, Tulia, Tex.

Filed July 18, 1963, Ser. No. 75,862

Term of patent 14 years

(Cl. D4—4)

Fig. 1.

Fig. 2.

Fig. 3.

Fig. 4.

Fig. 5.

Fig. 6.

FIG. 1 is a plan view of a body support for use in shampooing the hair showing my new design;

FIG. 2 is a side elevation of the same;

FIG. 3 is a view taken along the line 3—3 of FIG. 1 in the direction of the arrows;

FIG. 4 is an end view from the left in FIG. 2;

FIG. 5 is an end view from the right in FIG. 2; and

FIG. 6 is a view taken along the line 6—6 of FIG. 2 in the direction of the arrows.

I claim:

The ornamental design for a body support for use in shampooing the hair or the like, as shown.
